JACOB ABRAHAMSON, OF ASBURY PARK, NEW JERSEY.

IMPLEMENT FOR TRUING UP THREADS.

1,196,415.

Specification of Letters Patent. Patented Aug. 29, 1916.

Application filed January 25, 1916. Serial No. 74,071.

To all whom it may concern:

Be it known that I, JACOB ABRAHAMSON, a citizen of the United States of America, and resident of Asbury Park, in the county 5 of Monmouth and State of New Jersey, have invented certain new and useful Improvements in Implements for Truing Up Threads, of which the following is a specification.

10 This invention is an implement for truing-up threads, and is particularly adapted for truing-up the valve and cap threads of nipples of pneumatic tires, positioned interiorly and exteriorly, respectively, of the 15 nipple.

As is well known, the threads of the nipple frequently become worn, burred or distorted, thereby rendering it troublesome and difficult to insert the pneumatic valve 20 or apply the cap. The present invention permits of either the internal or external threads, or both, being readily and expeditiously trued-up or re-cut. The implement may operate on one set of threads at a time, 25 or on both sets simultaneously.

With the foregoing objects in view, the invention, speaking generally, embodies two thread-cutting elements operating in the same axis, means for mounting said cutter 30 elements in their operating positions on a nipple, and means for operating the cutters.

The specific form of the invention herein illustrated embodies a hand-wheel provided with a hub, interior of which is positioned a cutter for truing-up or re-cutting 35 the cap threads of the nipple, and exterior of the hub of the hand-wheel is positioned a sleeve extending beyond the end of the hub and adapted to fit over or embrace the 40 nipple. The hand-wheel is provided with a central, cylindrical passage, through which a stem extends, and positioned on one end of the stem is a second cutter for truing-up the valve threads of the nipple. A 45 second hand-wheel is fixed to the opposite end of the stem for the purpose of manually imparting rotation to the stem to effect the cutting operation. The cap thread cutter is actuated by its co-operating hand-wheel, and the valve thread cutter is actuated 50 by the hand-wheel secured to its stem, the sleeve serving to centralize the cutters and maintain them in operative position

upon the nipple during the cutting operation.

Features of the invention other than those specified, as well as the specific operation of the invention, will be apparent from the hereinafter detailed description taken in conjunction with the accompanying drawings.

In the accompanying drawings, I have illustrated one practical embodiment of the invention, but the construction shown therein is to be understood as illustrative, only, 65 and not as defining the limits of the invention.

Figure 1 is a side elevation of the implement of the present invention in operative position upon a tire nipple. Fig. 2 is a 70 vertical, central section therethrough, showing the cutters in retracted position. Fig. 3 is a like section, showing the cutters at the termination of their cutting operation, and Fig. 4 is a transverse section taken on line 75 4—4 of Fig. 3.

Referring to the drawings, A indicates a nipple of the type generally employed on pneumatic tires. As is well understood, the nipple is provided with a longitudinal 80 passage a, screw-threaded, as at a', near the free end of the nipple to allow of the insertion of the usual valve, not shown. A portion of the nipple near its free end is of reduced diameter and is also screw-threaded, as at a'', whereby a protecting cap may be normally screwed upon said nipple, or the cap of a tire pump may be temporarily secured thereon while the tire is being inflated.

It is well known that, in practice, the threads a' for the cap frequently become burred or distorted during the insertion of the nipple through the small aperture in the rim of a vehicle wheel, or from other 95 causes, whereas the valve threads a'' frequently become likewise distorted or gummed with oil, so as to render the insertion or removal of the valve very difficult.

According to the specific form of the invention shown, a cutter element B is provided, which cutter element embodies the standard threading employed on pneumatic tire nipples for the cap retaining means. This cutter element is shown as formed or 105 positioned within the hub c of a hand-wheel

C. Surrounding the hub, fixed thereto, and extending beyond the lower end of the same, is a sleeve D of substantially the same interior diameter as the diameter of nipple 5 A. This sleeve is, therefore, adapted to fit over the nipple in the manner shown in Fig. 2, whereupon the rotation of hand-wheel C will cause the cutter to operate upon the distorted threads a^2 and re-cut or true-up the 10 same.

Extending longitudinally through a central passage in hand-wheel C and hub e, is a stem E, the lower end of which carries a cutter element F, corresponding to the standard 15 valve threading of tire nipples. Upon stem E is fixed a hand-wheel e whereby stem E may be manually operated and the co-operating cutter F actuated. Stem E is preferably extended beyond hand-wheel e, and at 20 the end thereof is formed a valve-removing member e'. Member e' is adapted to be inserted into the longitudinal passage of the nipple and engage with the valve, whereupon rotation of the stem will remove the 25 valve and allow of the truing-up operation of the threads a' .

In employing the implement in the truing-up of the nipple threads referred to, said implement is positioned upon the nipple so 30 that the nipple extends into sleeve D. By grasping hand-wheel C and rotating the same, cutter B will be rotated, thereby truing-up or re-cutting the cap threads a^2 . If the valve threads a' are to be re-cut, the operation of applying the implement to the 35 nipple is the same as that described for truing-up the cap threads a^2 , but in the subsequent operation, instead of operating hand-wheel C, hand-wheel e is rotated. Thus, 40 cutter F is actuated to re-cut or true-up the valve threads a' , while hand-wheel C and its associated cutter B remain idle:

It will be manifest from the foregoing description, as well as from the accompanying 45 drawings, that either one of the cutter elements may be operated independently of the other. However, the length of stem E, between the base of hand-wheel e and its cutter F, is such that, when stem E is de- 50 pressed sufficiently to bring hand-wheel e into engagement with the upper face of hand-wheel C, the cutters F and B will be in juxtaposition. Such being the case, the parts may be brought into the positions specified, 55 whereupon the hand-wheels will be so associated that they may be grasped simultaneously by the hand of the operator and thus operated to re-cut or true-up both the threads a' and a^2 at the same time. The 60 cutters may, therefore, be used either singly or collectively in the carrying out of their functions.

The implement of the present invention is 65 of extreme simplicity and great utility and value, e. g., as a part of an automobilist's

tool kit. It is small, compact, efficient and easily operated in the carrying out of its functions, and, moreover, is so constructed that none of its component parts can get out of order or become broken.

In the form of the invention illustrated, the guiding sleeve D serves to hold the parts in place during the operation of the cutters, and this is the form which I prefer to employ. However, while this sleeve might be 70 dispensed with, the resulting structure would not operate with the same efficiency as in its preferred form, in so far as the positioning of the implement upon the nipple is concerned, although it would true-up or re-cut 75 the threads very well, even in the absence of the sleeve.

Having thus fully described the invention, what I claim as new, and desire to secure by Letters Patent, is:

1. A thread cutting implement embodying external and internal thread cutters, and separate and independent means for operating each cutter, said means being juxtaposed whereby the cutters may be operated 80 either separately or conjointly.

2. A thread cutting implement embodying external and internal thread cutters, a carrier member for supporting and actuating the external cutter, and a stem mounted on 95 the carrier member of the external cutter for supporting and actuating the internal cutter independently of the external cutter.

3. A thread cutting implement embodying external and internal thread cutters, a carrier member for supporting and actuating the external cutter, and a stem rotatably journaled in said carrier member for supporting and actuating the internal cutter 100 independently of the external cutter.

4. A thread cutting implement embodying external and internal thread cutters, each of which is operable independently of the other, a hand-wheel for separately actuating the external cutter and a hand-wheel for 110 separately actuating the internal cutter, the said hand-wheels being juxtaposed whereby both may be simultaneously grasped and both cutters actuated simultaneously.

5. A thread cutting implement embodying 115 external and internal thread cutters, separate and independent means for operating each cutter, said means being juxtaposed whereby the cutters may be operated either separately or conjointly, and means for 120 mounting said cutters for longitudinal movement and rotation in operative relation to the work to be done.

6. A thread cutting implement embodying 125 external and internal thread cutters, each of which is operable independently of the other, a hand-wheel for separately actuating the external cutter and a hand-wheel for separately actuating the internal cutter, the said hand-wheels being juxtaposed whereby both 130

may be simultaneously grasped and both cutters actuated simultaneously, and means coöperating with the cutters for mounting them in operative relation to the work to be done.

7. A thread cutting implement embodying an external thread cutter, means for actuating the same, an internal thread cutter mounted coaxially with and movable relatively to the external thread cutter, and means for separately actuating the internal thread cutter independently of the external thread cutter, the actuating means of both cutters being juxtaposed, whereby they may be simultaneously operated to simultaneously actuate both cutters.

8. A thread cutting implement embodying an external thread cutter, means for actuating the same, an internal thread cutter mounted coaxially with and movable relatively to the external thread cutter, means for separately actuating the internal thread cutter independently of the external thread cutter, the actuating means of both cutters being juxtaposed, whereby they may be simultaneously operated to simultaneously actuate both cutters, and means coöperating with the cutters for mounting them in operative relation to the work to be done.

9. A thread cutting implement for truing-up the valve and cap threads of pneumatic tire nipples, embodying a cap thread cutter element, means for mounting the same for longitudinal and rotary movement on a tire nipple, and means for rotating the cutter, in combination with a valve thread cutter, a stem thereon, said stem being

mounted for longitudinal movement and rotation on the cap thread cutter element and coaxial therewith, and means for rotating said stem to operate said cutter.

10. A thread cutting implement for truing-up the valve and cap threads of pneumatic tire nipples, embodying a cap thread cutter element, means for mounting the same for longitudinal and rotary movement on a tire nipple, and means for rotating the cutter, in combination with a valve thread cutter, a stem thereon, said stem being mounted for rotation and longitudinal movement on the cap thread cutter element whereby relative operative position of the cutters is maintained, and means for rotating said stem to actuate its cutter.

11. A thread cutting implement for truing-up the valve and cap threads of pneumatic tire nipples, embodying a cap thread cutter element, means for mounting the same for longitudinal and rotary movement on a tire nipple, and means for rotating the cutter, in combination with a valve thread cutter, a stem thereon, said stem being mounted for longitudinal movement and rotation on the cap thread cutter element and coaxial therewith, means for rotating said stem to operate said cutter, and means on the stem for removing the valve of the nipple.

Signed by me at New York city, N. Y., this 3rd day of January 1916.

JACOB ABRAHAMSON.
